UNITED STATES PATENT OFFICE

RUPERT IGNATIUS FARRELL, OF MONTREAL, QUEBEC, CANADA

LEVEL GATE

Application filed October 29, 1928. Serial No. 315,874.

The invention relates to a level gate as described in the present specification and illustrated in the accompanying drawings that form part of the same.

5 The invention consists essentially of the novel features of construction pointed out broadly and specifically in the claims for novelty following a description containing an explanation in detail of an acceptable form of the invention.

10 The objects of the invention are to furnish a device that will enable the motorists and others to know that a train is actually about to pass a level crossing and thereby 15 eliminate the danger of not seeing the train in sufficient time for stopping the vehicle; to save lives and loss of property by the erecting of barriers that will coincidentally close and open before and after the passing 20 of the trains across the highway; to devise a gate that will operate with equal satisfaction in the wintry weather as well as in the summer; to avoid complicated parts and 25 simplify the construction so as to reduce the cost of production and facilitate the operation; and generally to provide a railway level crossing gate that will be durable in construction and efficient in its operation.

30 In the drawings Figure 1 is a vertical sectional view of the box disclosing the operating mechanism and gate.

Figure 2 is a vertical sectional view at right angles to the sectional view shown in Figure 1 and disclosing the operating mechanism.

25 Figure 3 is a view of the gate extended to shut off the road.

Figure 4 is a plan view of the bearing bracket for the rocker arms.

40 Like numerals of reference indicate corresponding parts in the various figures.

45 Referring to the drawings the box enclosing the operating mechanism of the gate is indicated by the numeral 10 and contains the bracket 11 in its upper portion and which is firmly secured to the box wall 12.

50 The bracket 11 has the bearing members 13 and 14 for the upper rod 15 and the lower rod 16 supporting the rocker arms 17 and 18 respectively.

The rocker arm 17 has suspended at one end the counter balance weight 19 and at the other end is centrally connected by the link 20 to the cage 21 formed of the platform 22 and the yoke 23.

55 The cage 21 has centrally secured to the underside of the platform 22 the sliding actuating member 24 which is held in a vertical position by the guides 25 and 26 secured to the box wall 27 and abuts the roller 41 secured by the bracket 42 to the box wall 27.

60 The gate is formed by a plurality of pivoted bars 28 in lazy tong formation, the inner ends of the inner bars 29 and 30 being pivotedly secured to a bracket 31 rigidly held to the box wall 27 and to the sliding actuating member 24 respectively. The buffer bar 32 is secured to the pivots 33 one of said pivots sliding in the slot 34 in said 65 buffer bar, the other pivot pivotally securing the bar to the gate at the lower end of said bar, the castor wheel 35 is swivelly mounted at the lower end of the buffer bar and forms a support for the gate in its extension and contraction movements.

70 The rocker arm 18 suspends at one end the weight 37 which is supported on the platform 22 of the cage 21 and at the other end is connected and controlled by the solenoid 80 rod 38 operated by the solenoids 39 and which is connected to a suitable signal system.

75 The semaphore 40 at the top of the casing 10 is also connected to suitable signal 85 system.

80 The means for operating the rocker arms are of course not confined to the solenoid arrangement but may be accomplished mechanically or by other convenient means according to the requirements.

85 In the operation of the invention when a train approaches a level crossing it closes a circuit included in a signal system which is connected to the solenoids or other means 90 controlling the rod operating the rocker arms. The connecting rod rocks the rocker arm which suspends the weight supported on the platform of the cage, and the cage 95 released by the weight is lifted upwardly by 100

the other rocker arm having the counterbalance weight. The actuating member secured the cage is also raised thereby sending the lazy tong bars to their extended position and forming a barrier across the road until the train has passed and immediately thereafter the lower rocker arm is released and the weight it carries forces the cage back to its normal position and lowers the actuating member and which closes the gate.

What I claim is:-

1. In a level gate a collapsible bar gate and operating means comprising a balance arm having suspended weights from one end and an operating weighted bar pivotally secured to the other end and to the gate and a rocker arm having the weights of said operating bar attached to one end for relieving the weight on said bar and a motive power attached to the other end.
2. In a level crossing gate a collapsible bar gate and operating means comprising a balance arm having a pivotally suspended weight at one end and a link connecting the other end of said arm with a cage fixedly secured to a gate post slidably secured in suitable bearings, a counter weight resting on said post in said cage, a rocker arm adapted to lift off said counter weight from said post and a motive power at the other end of said rocker arm.
3. In a level crossing gate a collapsible gate and operating means comprising a balance arm carrying an operating suspended weight at one end, a link pivotally secured to the other end, a cage for carrying a weight counter balancing the aforesaid weight and link, an operating post secured to said cage, a rocker arm pivotally secured to said cage weight and adapted to lift it independently off said cage to release the balance arm weight and actuate said post and a solenoid suitably energized and attached to the other end of said rocker.

45 Signed at Montreal, Canada, this 1st day of October, 1928.

RUPERT IGNATIUS FARRELL,
